UNITED STATES PATENT OFFICE

WILLIAM GORDON, OF UNION, NEW JERSEY

SCREW-ACTUATED VISE

Application filed April 22, 1927. Serial No. 185,737.

This invention relates to improvements in screw-actuated vises.

One of the objects of this invention is to produce a screw-actuated vise which will have all the advantages of a screw-actuated vise for adjusting or tightening up upon the object which it is desired to secure, and, in addition, will be capable of quick manipulation to an approximate gripping position.

10 Another object of the invention is to produce a screw-actuated vise, comprising a stationary jaw and a movable jaw slidable relatively thereto which are capable of being tightened up on an article by the cooperative engagement of a screw and nut, and in which during initial or approximate adjustment of the jaws, the screw and nut may be automatically released from such cooperative engagement to enable quick adjustment.

15 Another object of the invention is to produce a screw-actuated vise in which a movable jaw is instantaneously and manually releasable from screw-operative engagement, and upon such manual release, will be automatically moved to full open position.

20 Still another object of my invention is to produce a screw-actuated vise in which one of the jaws is normally movable and adjustable in gripping relation to the other by relative rotation of a cooperating screw and nut but in which the nut is preferably a sectional nut and the engagement between the cooperating threads of the screw and nut is yielding so that the movable jaw may without 25 relative rotation of the screw and nut, by direct pushing movement be moved from open position to an approximately-closed gripping position, the engagement of the screw and nut being automatically released during

30 such initial closing movement which causes the threads of the screw to click over the threads on the sectional nut into an approximate or initial position for engaging the object to be operated upon and this feature is

35 preferably combined with the further feature that the cooperative engagement of the screw and nut is manually releasable and upon such manual release the movable jaw will be automatically moved by an opening spring into 40 full open position.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:—

Fig. 1 is a vertical section substantially on the line 1—1 of Fig. 2;

Fig. 2 is a plan view of the vise shown in Fig. 1; and

Fig. 3 is a section on the line 3—3 of Fig. 1.

Referring now to these drawings, which illustrate a preferred embodiment of my invention, 1 indicates a body portion of a vise having an attaching base portion 2 which may be attached to a suitable bench or support 3 by screws, 4, 4', 4''. The upper end of the vise is provided with a stationary jaw 5 and a horizontal cavity 6 is provided for the reception of a sliding shank portion 7' of a movable jaw 7. Said movable jaw 7 is preferably provided with a cavity 9 preferably opening 75 downwardly and extending from a solid head portion 10 to a solid tail portion 11. Mounted within the cavity 9 with its opposite ends rotatably supported in the head portion 10 and tail portion 11, is a tightening screw 12. 80 As illustrated, the screw 12 is provided at its rear end with a journal 12' which is mounted in a bearing aperture 11' in the tail piece at the rear end of the said shank 7, and adjacent to its opposite outer end 10' in a bearing 85 aperture in the head portion 10 and having at its opposite end a cylindrical head 13 provided with a slidable handle bar 14 of conventional construction, said head 10 being also, as shown, provided with a collar-gravity 90 15 within which is fitted a locking collar 16 fastened by set screws 16' to the unthreaded portion 12'' of the screw 12.

Communicating with the horizontal aperture 9 within the body of the vise and intersecting the same at a right angle is a vertical aperture 17, and mounted in said aperture 17 is a sectional nut 18 having its threads 19 yieldingly pressed into engagement with the threads 12'' of the screw 12 by a spring 100

20 abutting at one end against the bottom 18' of the said nut and at the other end against a closure plate 21 for the aperture 17, which closure plate is preferably set in a depressed seat 23 so that its outer surface is 5 flush with the bottom surface of the base portion and is fastened thereto by screws 22.

The screw threads 12^b have, as shown, a forward inclination and the threads 19 on 10 the sectional nut 18 have a complementary inclination. It will be seen that the threads of the nut 18 are thus, by pressure of the spring 20 forced yieldingly into engagement with the threads 12^b of the screw, and that the 15 inclination of the screw threads and nut threads is such that direct manual inward pressure on the movable jaw will cause an automatic releasing or disengagement of the threads of the nut from the threads of the screw and such manual movement will cause 20 a clicking of the threads of the screw over the nut threads, so as to enable the movable jaw 8 to be moved to its approximate gripping position.

In the preferred embodiment of my invention means for manually releasing the threads of the sectional nut from the threads of the screw is provided and upon such manual release of the threads of the screw, the shank 30 of the movable jaw 7 is automatically forced outwardly by a spring 24 to cause a movement of the movable jaw to full-open position and, as illustrated, I provide finger-actuated means which, as shown, comprises finger 35 pieces 25, 25' having shanks screwed into the sides of the sectional nut 18 and extending through elongated openings 26, 26' at opposite sides of the body portion 1 of the vise. Upon depressing one or both of the finger pieces 25, 25' the jaw 7 will immediately, 40 by the pressure of the spring 24, be automatically moved to full-open position.

In the construction shown, the spring 24 has one end portion mounted in a cavity 27 formed at the rear end 11 of the shank of the jaw 8, said spring being so mounted in this cavity with its end abutting against the inner vertical wall thereof, while the opposite end of the spring abuts against the inner surface 28' of an enclosing tube 28 suitably 50 mounted on the rear end of the body portion 1 of the vise and, as shown, having side flanges 28^a fastened by screws 29 to the rear face of said body portion. This tube not only encloses the spring but prevents the access of dirt and filings to said spring and to the screw.

When the sectional nut is manually released, as aforesaid, and the jaw moved to its full open position by means of the spring 24, the shoulder 11^a will contact with the side surface 18^a of the sectional nut which shoulder and surface form limiting stops to prevent excessive outward movement by the 65 spring.

The operation of the preferred form of device shown is as follows:

Assuming that it is desired to grip a piece of material between the jaws, which at the time may be in any given position, the finger pieces will be manually operated to cause the jaws to be moved to full open position in which position the shoulder 11^a will engage the side of the sectional nut 18^a. The article to be gripped is then inserted between the jaws and the jaw 8 is slid or moved manually against the action of the spring 24 into an initial adjusted position, the engagement of the threads of the screwed nut being yielding is, during this sliding movement, automatically released, the threads of the screw clicking over the threads of the sectional nut as the same is manually slid over the same. The jaw 8 is now further tightened upon the article by rotation of the screw in the conventional manner through the conventional bar handle 14. During this rotating movement of the screw the sectional nut, which fits snugly within its mounting aperture 17, will enable a tightening movement of the jaw 8, 20 and I have found that a strong, tight, grip in all respects as tight as in the ordinary screw and nut may be obtained upon the article and there is no danger of a slipping of the teeth during this rotating movement 95 of the screw.

It will be seen that the operating parts of the vise mechanism such as the screw and nut as well as the springs are all completely enclosed and may be, therefore, kept free from 100 dust, chips, filings and the like.

Having described my invention, I claim:

1. A vise embodying, in combination, a supporting body portion, jaw members, one of which is relatively stationary and the other movable relatively thereto, a screw connected with one of such jaw members and mounted thereon for rotary movement only, a sectional nut mounted for vertical movement only and having a connection with the other jaw member and provided with threads arranged to be operatively engaged with the threads of said screw, the threads of said screw and nut having complementary inclined sides arranged to permit a relative sliding movement in one direction, spring means for normally pressing the threads of said sectional nut into engagement with the threads of said screw, whereby direct manual pressure against the movable jaw will permit a clicking of the threads of the screw over those of the sectional nut to produce a quick movement of the movable jaw, means for manually disengaging the threads of said sectional nut and screw, and a spring normally cooperating with the first mentioned spring means to press the inclined threads of the screw into engagement with the inclined threads of the sectional nut and also opera- 130

tive upon manual disengagement of the nut to move the jaws into full open position.

2. A vise comprising a supporting body portion provided with a fixed jaw and having a horizontal cavity, a movable jaw having a shank portion slidable within said cavity in the supporting body portion, a screw having screw threads mounted for rotary movement only within said shank portion of the movable jaw, a sectional nut mounted to have vertical movement only in said supporting body portion and provided with threads arranged to have an operative engagement with the threads of said screw, means for yieldingly forcing the threads of said sectional nut into engagement with the threads of said screw, and a spring arranged in a spring-enclosing casing connected to the rear end of the body portion and adapted upon manual release of said screw threads to move the movable jaw into full open position.

3. A vise comprising a supporting body portion provided with a fixed jaw and having a horizontal cavity, a movable jaw having a shank portion slidable within the cavity in said supporting body portion, a screw having screw-threads mounted for rotary movement only within said shank portion of the movable jaw, a sectional nut mounted for vertical movement only in said supporting body portion and having threads arranged to have an operative engagement with the threads of said screw, said screw threads of the nut and screw having complementary inclinations to permit sliding movement in one direction, a spring for yieldingly forcing the threads of the sectional nut in operative engagement with the threads of the screw, means for rotating said screw to cause a tightening movement of the movable jaw in relation to the fixed jaw, means for manually disengaging the threads of said nut and screw to permit movement of the movable jaw in relation to the fixed jaw, and a spring normally cooperating with the first mentioned spring to press the inclined threads of the screw into engagement with the inclined threads of the sectional nut and also to force said jaws into full open position upon manual release of the engagement of said screw threads against the action of said first mentioned spring.

In witness whereof, I have signed my name to the foregoing specification.

WILLIAM GORDON.
